UNITED STATES PATENT OFFICE.

CHARLES HANSGEN, OF NEW YORK, N. Y., ASSIGNOR TO AUTO HEATER AND VENTILATOR CORPORATION, A CORPORATION OF NEW YORK.

HEATING SYSTEM FOR AUTOMOBILES.

1,182,907.

Specification of Letters Patent.

Patented May 16, 1916.

Application filed December 8, 1915. Serial No. 65,658.

To all whom it may concern:

Be it known that I, CHARLES HANSGEN, a citizen of the United States, residing at No. 133 West Sixty-fourth street, in the 5 city of New York and State of New York, have invented certain new and useful Improvements in Heating Systems for Automobiles; and I do hereby declare the following to be a full, clear, and exact description of the invention, such as will enable 10 others skilled in the art to which it app pertains to make and use the same.

My present invention relates to an improved and effective means for heating automobiles operated by means of heat engines, and has for its particular object the provision of an apparatus of a simple and inexpensive character and capable of being readily applied to automobiles without changing 20 their construction, and whereby a positive supply of hot air may be forced into the vehicle at a convenient point or points, and preferably in the floor.

The invention is illustrated in the accompanying drawings, in which—

Figure 1 is a side view of an automobile provided with my invention, the side being broken away sufficiently to show my apparatus in position, Fig. 2 is a vertical section of the heating casing shown in position on the exhaust pipe, Fig. 3 is a top plan view of said casing, and Fig. 4 is a cross sectional view of said casing on the line 4, 4 in Fig. 3.

In carrying out my invention I place a suitable heating casing in a position to embrace a portion of the length of the exhaust pipe, and connect one end of said casing with a conduit leading to a point just behind the ventilating fan while the other end of the casing, or some suitable portion thereof, is connected by a conduit or conduits at a point or points of discharge for the hot air at suitable locations in the body of the 45 automobile, preferably in the floor.

In the drawing, the body of the automobile is shown at 10, and the engine at 11, the latter being supplied in any well known manner with a ventilating fan 12. The 50 exhaust manifold is shown at 13, the same being supplied with the usual exhaust pipe 14, leading to a point near the rear of the automobile in the usual manner.

The heating casing is preferably a metal 55 box composed of two parts, 15 and 16,

hinged together as at 17, and provided with lugs 18 and 19 adapted to come together to receive bolts 20 for the purpose of closing the box. At the ends of the box are semi-circular openings which together form the 60 terminal circular opening 21, at each end to accommodate the exhaust pipe 14. The entrance and exits for the air to be heated may be at any suitable points in the casing, but are preferably placed at the two ends of 65 the upper division 15, as shown at 22 and 23, respectively. This arrangement of the nipples 22 and 23 is found convenient to accommodate the casing and the conduits to the present disposition of the parts in typi- 70 cal automobiles.

The cold air is brought to the nipple 22 at the forward end of the casing by the conduit 24, whose forward end is placed just behind the fan 12, and is preferably 75 provided with a funnel 25 to assist in collecting the air, this tube is preferably of the well known flexible metallic type, and is secured preferably in such a manner as to lie along, and in contact with, as much as 80 possible, of the manifold 13, and the pipe 14 leading from it.

From the opposite nipple 23 one or more protected heating air pipes 26 are laid to one or more suitable gratings or registers 27, 85 preferably in the floor of the automobile. These pipes are protected by asbestos or the like in any well known manner so as to prevent escape of heat, except at the point of discharge of the air.

The connection of the conduit with the casing 15, 16 and with the grating 27 is accomplished by the well known hose unions or in any desired manner.

It will be seen that the construction of 95 my device is adapted for easy application to standard types of automobiles without disturbance in their construction, and by means so simple as to permit adjustment by unskilled persons, and without sending the 100 car to a specially equipped shop.

What I claim is:

A heating attachment adapted to be readily applied to automobiles provided with an internal combustion engine, an exhaust pipe, and a cooling fan, comprising a casing made of two members hinged together at one side and provided with a flanged joint at the opposite side, each member being provided with a semicircular ap- 110

erture in each end thereof adapted to fit snugly over the exhaust pipe and form therewith a closed chamber, an inclined nipple projecting upwardly and outwardly from each end of the upper member of said closed casing, a flexible metallic pipe leading from the fan to the forward nipple and laid in contact with the heated exhaust pipe leading from the engine, and delivering

warmed air to said closed chamber, a pipe 10 connecting the rear nipple with the interior of the car, and a register located in the car floor for controlling the flow of warmed air through said second pipe into the car, substantially as described.

In testimony whereof, I have affixed my signature.

CHARLES HANSGEN.
